A CORPORATION OF MASSACHUSETTS

RATCHET SCREW DRIVER

Application filed June 23, 1925. Serial No. 38,951.

This invention relates to a screwdriver, and specifically to an improved screwdriver of the ratchet type.

It is an object of the invention to provide a device of the type stated which will efficiently perform the purposes for which it is intended, and which will also be economically and readily manufactured and easily assembled.

10 A further object is that of furnishing a tool of this nature of relatively simple and improved construction which may be utilized to advantage to withdraw screws and similar articles, as well as to drive them home.

15 A still further object is that of constructing a screwdriver of the type mentioned and in such a manner that the relatively movable parts will continue to function without need of replacement or adjustment over long periods of heavy duty.

20 With these and further objects in mind, the invention accordingly comprises the features of construction, combination of elements, and arrangement of parts which will be exemplified in the construction hereinafter set forth and the scope of the application of which will be indicated in the claims.

25 For a fuller understanding of the nature and objects of the invention reference should be had to the following detailed description taken in connection with the accompanying drawings, in which:

30 Fig. 1 is a side elevation of one type of screwdriver embodying the improved construction of the present invention;

35 Fig. 2 is an enlarged sectional side view of certain of the operating mechanism of the tool;

40 Fig. 3 is a side elevation of this portion of the tool with the exterior knurled member removed therefrom;

45 Fig. 4 is a similar view with the pawl-actuating sleeve removed;

Fig. 5 is a transverse sectional view taken along the lines 5—5 of Fig. 4; and

50 Fig. 6 is a view similar to Fig. 5, but taken along the lines 6—6 of Fig. 1 and showing a different form of pawl-actuating spring from that employed in the preceding figures.

It is here to be observed that in the illus-

trated embodiment the invention has been shown in connection with a ratchet screwdriver of the single spiral type.

While the invention in certain respects primarily aims to provide an improved tool of this character, it will, nevertheless, be appreciated that the several features of the invention hereinafter more fully described may be utilized to advantage in association with screwdrivers of other types.

Thus, referring particularly to Fig. 1, the numeral 10 indicates a handle secured to one end of a tube 11, and secured to the opposite end of this tube is a pawl-controlling member, generally indicated at 12. Retractable within the tube is a spindle 13 formed in the present instance with a single spiral groove 14. A spring 15 serves to normally project the spindle within the tube, it being observed that a cushioning block 16 may be interposed between the spindle and spring ends, and that access to the interior of the latter member may be had through a cap 17, which when removed obviously permits of withdrawal of the spring, as well as the block.

Secured to the opposite end of the spindle 13 is a chuck 18, which may be of any desired type, and to the rear of this chuck a preferably knurled sleeve 19 may be rotatably mounted in order to provide a convenient gripping surface for the fingers of the operator.

Now, referring to the detailed construction of the pawl-actuating member, attention is primarily invited to Figs. 2 to 5 inclusive, in which it will be noted that a housing 20 is fixedly secured to the outer end of the tube 11 and provides a frame or body, which, in addition to other functions, serves as a pawl mounting, and to the outer end of which a headed nut 21 may be secured by means of the threads 22, this nut being normally locked by means of a key 23 extending through a slot formed in the outer end of the member 20. At the opposite, i. e., the inner, end of the member 20 a collar 24 is mounted upon the tube, and this collar extends beyond this member and has a circumference substantially equal to the circumference of the nut 21. In order to prevent an accidental loosening of

60

90

95

100

the collar 24 any desired expedient may be resorted to, for example, as has been illustrated, a spring may be interposed between the outer edge thereof and the inner edge of the frame member.

5 This member may be formed with two longitudinally-extending slots 25 and a pair of arcuate grooves 26 intersecting the slots 25. Having their bodies 27 disposed one within each of the slots 25 is a pair of pawl members, one of these members being provided with a pair of relatively short arms 28 extending at rightangles to its body and within these grooves 26, while the second of the pawls is 10 provided with corresponding arms 29, which likewise extends one within each of the grooves 26 and in a direction opposite to the direction in which the arms 28 extend, it being here noted that the arms 29 are of greater 15 length than the arms 28. Thus, the pawl of which the arms 28 form a part will at all times remain operative, while the pawl which presents arms 29 will be actuated in a manner hereinafter specified.

20 25 Bearing against the inner circumferential edge of the nut 21 is a tube 30 having its inner face provided with a pair of opposed ribs 31, which are disposed in a spiral corresponding to the spiral of the grooves 14, the outer surface of the tube 30—and more particularly—the central portion thereof being provided with an annular series of teeth 32 furnishing a ratchet portion. Thus, the tube 30 serves as a ratchet nut, and is restrained against movement other than rotational by virtue of the fact that its outer edge bears against the inner edge of the nut 21 as aforesaid, and that its opposite edge bears against a collar 33 loosely encircling the spindle 13 and arranged adjacent the outer edge of the tube 11.

40 45 In order to normally urge both pawls into contact with the ratchet portion 32 an H-shaped spring 34 may be employed, which has the outer end of its arms bowed to extend inwardly so as to press the pawls adjacent the outer ends of their bodies, the central portion of this spring thus extending upwardly and out of contact with the pawl bodies.

50 55 A sleeve 35 encircles the member 20 and has its opposite end edges bearing against the nut 21 and collar 24 so that it is restrained from longitudinal movement relatively to the tool handle. Likewise, a further sleeve 36 encircles the sleeve 35, the outer surface of the sleeve 36 being preferably knurled so as to afford a convenient handgrip, it being observed that the circumference of the nut 21 and collar 24 is sufficiently great to also prevent movement other than rotative on the 60 65 part of this sleeve. The sleeves 35 and 36 are normally coupled together in any desired manner. For example, the former may be formed with a notch 37, and the latter may carry a projection 38 riding in this notch to accomplish the desired result. Rotative move-

ment of the sleeve 35 with respect to the other pawl-supporting and actuating mechanism may be limited by forming that portion of the sleeve edge which rides adjacent the key 23 with an arcuate notch 39 and extending 70 the head of the key 23 to project into this notch.

75 Thus, it will be understood that the central portion of the spring 34 will bear against the inner face of the sleeve 35 and be consequently maintained under tension. If for some reason it is not desired to utilize a spring of this character it will be obvious that a different type of spring may be employed, for example, as has been illustrated in Fig. 6. In this view 80 the ratchet nut housing is formed with an annular groove 40, preferably having a depressed portion 41 and being interrupted of course by the slots 25. Disposed within this groove is a spring 42, which has its extremities bent to extend inwardly as at 43 and bear against the pawls, and intermediate these extremities it is formed with an inwardly-struck portion 44, which rides within the depression 41 and thus prevents the spring from 85 creeping circumferentially.

90 95 From the foregoing it will be appreciated that in operation the shifter sleeve 36 is turned to correspondingly turn the sleeve 35 so that arcuately-extending slots 45 formed in this sleeve and in line with the arms 29 of the pawl member will move to a position at which these arms are swung inwardly within the grooves 26. Thus, this pawl member is rocked so that its body 27 rises upwardly within the slot 25, and its lower edge consequently does not engage the ratchet of the nut. This rocking occurs around the inner edges of the grooves 26 and adjacent the outer edge of the corresponding slot, these 100 grooves' edges thus acting as a fulcrum. Despite the fact that one of the pawl members is thus rendered inoperative, the second pawl member will remain in contact with the ratchet portion 32 of the sleeve 30. As a consequence, if an operator grips the handle 10 and the sleeve 19 and moves them towards each other, a screw which may be engaged by a bit carried by the chuck 18 will be driven. Upon the handle being permitted to move rearwardly following the urging of the spring 15, the engagement of the screw-head and bit will serve to prevent any tendency of the spindle 13 moving, due to frictional contact of the parts. The ratchet-nut will rotate, however, during such rearward movement, and the pawl, which has previously served to rotate the spindle, will now simply override the ratchet teeth of this nut.

110 115 120 125 130 These operations may be continued as long as desired, and if subsequently it is desired to withdraw a screw or screws this may readily be accomplished by simply rotating the shifter sleeve 36, and, consequently the sleeve 35, to a position at which the slots 45

permit the arms 29 of the second pawl member to swing outwardly, so that the body of the same may move downwardly within the slot 25 and to a position at which it will engage the ratchet of the nut. Under such conditions it will be obvious that upon the handle 10 being projected towards the sleeve 19 the spindle will be rotated as aforescribed, but upon retraction of the handle the spindle will be rotated in an opposite direction. Consequently, after the handle has been projected so that the spindle is housed to a maximum extent within the tube 11, and the sleeve-carrying portion of the chuck has its rearmost edge engaging the outer face of the nut 21, the handle 10 may be rotated as in the manner of an ordinary screwdriver to effect a retraction or withdrawal of the screw which is engaged by the bit associated with the chuck.

Thus, a tool has been provided which may be economically constructed, particularly if the screwdriver is of that type shown in the illustrated embodiment. Furthermore, a tool of this nature will be rugged in construction and its parts will operate in such a positive manner that it may be depended upon to continue to properly function over long periods of time and under heavy duty, without need of replacement or adjustment. In this connection, it will be appreciated that incident to the relatively large contact area extent between the pawls and ratchet teeth of the nut, the life of these parts will be greatly increased, and furthermore, if a single spiral is resorted to, the life of the ratchet nut will be further prolonged incident to the fact that it does not traverse double and intersecting spirals with their consequent sharp edges.

In addition, when it does become necessary to inspect or repair the tool, this may readily be done by simply removing the collar 24, which permits of the removal of the sleeves 35 and 36. If complete disassembly is desired, the key 23 may thereupon be removed and the nut 21 unscrewed so as to render all parts accessible.

Thus, among other, the objects specifically aforementioned are accomplished, and since certain changes may be made in the above construction, and different embodiments of the invention could be made, without departing from the scope thereof, it is intended that all matter contained in the above description, or shown in the accompanying drawing, shall be interpreted as illustrated and not in a limiting sense.

It is also to be understood that the following claims are intended to cover all of the generic and specific features of the invention herein described and all statements of the scope of the invention which as a matter of language might be said to fall therebetween.

Having described our invention, what we

claim as new and desire to secure by Letters Patent is:

1. A ratchet tool, including, in combination, a spindle formed with a spiral groove, a ratchet nut encircling said spindle and formed with a projection entering said groove, a housing enclosing said nut and formed with a H-shaped slot and recesses in its outer face extending away from the arms of said slot, a pair of pawls having their bodies disposed one in line with each of said slots, arms forming a part of said pawls and arranged within said recesses, the arms of one of said pawls being longer than the arms of the second of the same, a sleeve rotatably encircling said housing and formed with slots for the accommodation of the longer pawl arms, and a spring bearing against said pawls and tending to force the same into contact with the ratchet portion of said nut. 85

2. A ratchet tool, including, in combination, a spindle formed with a single twist groove, a ratchet nut surrounding said spindle having a plurality of longitudinally-disposed external projections and an internally-disposed projecting portion engaging the groove of said spindle, a sleeve encircling said nut and rotatable with respect thereto, said sleeve being formed with an opening, a pawl having a longitudinally-disposed portion adapted to engage said external projections of said ratchet nut and having a transversely-disposed arm in line with said sleeve opening and projecting into the same, means providing a fulcrum for said pawl whereby, upon said sleeve being shifted to engage said arm, said pawl will be swung radially upon its fulcrum and out of engagement with said internal projections of said ratchet nut, said pawl in its initial position engaging said projections. 105

3. A ratchet tool, including, in combination, a spirally-grooved spindle, a sleeve encircling said spindle and telescoped thereover, a ratchet nut within said sleeve and having a plurality of longitudinally-disposed external projections and internally-disposed projection engaging the groove of said spindle, a pawl disposed within said sleeve and adapted to engage one of the external projections of said ratchet nut constantly to prevent rotation thereof in one direction; a second pawl opposed to said first-named pawl and having a longitudinally-disposed portion adapted to engage said external projections of said ratchet nut and having a transversely-disposed arm, and means providing a fulcrum for said pawl and arm, said sleeve being formed with an opening for the accommodation of said arm and being movable to engage said arm and to swing said pawl radially on said fulcrum to move said pawl out of contact with said external projections of the ratchet nut. 125

4. A ratchet tool, including, in com-

bination, a spindle, a ratchet nut associated therewith for rotating said spindle and having a plurality of longitudinally-disposed external projections, a pawl mounted adjacent said nut and having a longitudinally-disposed portion adapted to engage an external projection thereof, said pawl having a transversely-extending arm, means providing a fulcrum for said pawl and arm, and 5 a sleeve disposed externally of said nut, said sleeve being formed with an opening for the accommodation of said arm and being movable to engage said arm and to swing said pawl radially on said fulcrum to move said pawl out of contact with said external projections of the ratchet nut.

5. A ratchet tool, including, in combination, a spindle, a ratchet nut associated therewith for rotating said spindle and having a plurality of longitudinally-disposed external projections, a pawl mounted adjacent said nut and having a longitudinally-disposed portion adapted to engage an external projection thereof, said pawl having a trans- 10 versely-extending arm, means providing a fulcrum between said pawl and arm whereby the pawl may be swung radially into and out of engagement with said external projection of the ratchet nut, and manually-operable 15 means for engaging said arm to move said pawl out of contact with said external projection.

6. A ratchet tool, including, in combination, a handle, a spindle extending into said 10 handle, a ratchet nut disposed within said handle and associated with said spindle for rotating the same, said nut having a plurality of longitudinally-disposed external projections, a sleeve non-rotatably associated 15 with said handle and encircling said nut, said sleeve having a longitudinally-disposed opening and a transversely-extending external groove intersecting said opening, a pawl having a portion lying within the longitudinally-disposed opening of said sleeve and having a transversely-extending arm in registry with the transverse groove of said sleeve, said pawl and arm being fulcrumed upon the juncture edge of the opening and 20 groove of said sleeve and having its longitudinal portion engaging an external projection of said ratchet nut; a second sleeve encircling said first sleeve, said second sleeve being formed with an opening for the accommodation of said arm and being movable with respect to said first sleeve to engage said arm and to swing said pawl out of the path of said external projections of the ratchet nut.

60 7. A ratchet tool, including, in combination, a handle, a spindle extending into said handle, a ratchet nut disposed within said handle and associated with said spindle for rotating the same, said nut having a plurality of longitudinally-disposed external 65

projections, a sleeve non-rotatably associated with said handle and encircling said nut, said sleeve having a longitudinally-disposed opening and a plurality of spaced transverse grooves intersecting said opening, a pawl having a portion lying within the longitudinally-disposed opening of said sleeve and having transversely-extending arms in registry with the transverse grooves of said sleeve, said pawl and arm being fulcrumed upon the juncture edge of the opening and groove of said sleeve and having its longitudinal portion engaging an external projection of said ratchet nut; a second sleeve encircling said first sleeve, said second sleeve being formed with an opening for the accommodation of said arm and being movable with respect to said first sleeve to engage said arm and to swing said pawl out of the path of said external projections of the ratchet nut.

In testimony whereof we affix our signatures.

DONALD B. SWAIN.
